UNITED STATES PATENT OFFICE.

GEORGE WONSOWICZ, OF FORKS, NEW YORK, ASSIGNOR OF ONE-HALF TO HENRY J. RALICKI, OF FORKS, NEW YORK.

DESIGN FOR A CURTAIN AND SHADE BRACKET.

61,024.

Specification for Design.

Patented May 30, 1922.

Application filed January 27, 1921. Serial No. 440,505. Term of patent 7 years.

To all whom it may concern:

Be it known that I, GEORGE WONSOWICZ, a citizen of Poland, residing at Forks, in the county of Erie and State of New York, have invented a new, original, and ornamental Design for a Curtain and Shade Bracket, of which the following is a specification, reference being had to the accompanying drawing, forming part thereof.

The figure in the drawing is a perspective view of a curtain and shade bracket showing my new design.

I claim:

The ornamental design for a curtain and shade bracket, as shown.

GEORGE WONSOWICZ.
